UNITED STATES PATENT OFFICE.

JAMES E. DOYLE, OF CLEVELAND, OHIO.

APPLIANCE FOR DISTRIBUTING A FLUID.

1,098,432.

Specification of Letters Patent.

Patented June 2, 1914.

Application filed November 23, 1912. Serial No. 733,082.

To all whom it may concern:

Be it known that I, JAMES E. DOYLE, a citizen of the United States, residing at Cleveland, in the county of Cuyahoga and State of Ohio, have invented a new and useful Improvement in Appliances for Distributing a Fluid, of which the following is a specification, the principle of the invention being herein explained and the best mode in which I have contemplated applying that principle, so as to distinguish it from other inventions.

The above entitling of my invention is broad in its scope. A specific association of the conception is with the printing art; while still more particular reference may be had, for the exemplifying purpose in hand, to the relative control mechanism of the several transferring rollers commonly used in conjunction with an ink distributing disk.

One object of my invention is to provide a mode for substantially completing the measure of increased efficiency, so that the distribution of the ink over the type will be still more uniformly accomplished prior to each impression therefrom.

Another object is the provision of mechanism which will be simple, economical of manufacture, readily attached or substituted and satisfactorily adjustable as the requirement may be.

The inventive conception is embodied in means which are hereinafter explained and variously combined in the claims, while the annexed drawing and particular description thereof together set forth in detail one certain means constituting my invention, the disclosed means however being but one of various mechanical forms in which the principle of my invention may be applied.

Referring now to the drawing in which like characters of reference consistently designate like parts in the several figures: Figure I is a side elevation of an appliance embodying my invention, mounted upon an upper part of the printing press and showing the immediate actuating member of the latter partially broken away. Fig. II is a top plan of the contrivance proper, Fig. III is a section on line III—III of Fig. I looking in the direction of the arrows.

The main construction of the printing press as such, includes a base frame, actuating contrivances and essential inter-connecting details, all assumed to be disposed in a feasible manner and hence as neither neces-

sary to be shown in the drawing, nor requiring specific description here. Accordingly, only that actuating member of the entire press which does directly articulate with, and propel the relative movement of, my inventive elements will be hereinafter considered. The upper portion of the frame constitutes the support for the usual pair of obtuse angled tracks 1 in vogue in presses embodying this specific kind of action. These tracks accordingly have apexes 2 incidental to their angular formation. Positioned between the upper portions of the tracks in any suitable manner is an ink distributing disk 3 and similarly disposed in some approved fashion between the lower disposed portions of the track is a type-form 4. Located laterally adjacent one of the tracks and conforming substantially thereto in contour so as to lie within substantially the same planes, is an angular rack 5 indicated as secured through the medium of screws 6. It is upon these tracks that the roller carriage or saddle 7 is designed to travel up and down with a reciprocal movement. Such motion, as has been earlier stated, will be assumed to be directly imparted through the medium of two saddle rods 8 partially seen in Figs. I and III. Each of these rods articulates with the saddle through the medium of pins 9. Interiorly positioned upon one of these pins and specifically upon that one which is disposed on the same side with the rack 5 and moreover in the same vertical plane, is a driving gear 10 adapted to mesh with and reciprocate along the rack 5 as will be readily understood. It is by the employment of power communicated through and hence actuating the rods 8, that the reciprocal travel of the saddle 7 is effected.

The opposite lateral ends of the saddle when upon the track comprise respectively an upwardly and a downwardly projecting bracket 11 and 12. Depending from opposite ends of these brackets are the members 13 and 14 respectively, adapted to serve as bushing supports for the roller shafts 15 and 16 respectively. Each of these shafts has mounted on opposite ends subsidiary rollers 17 and 18 and it is these which are adapted to traverse the tracks 1 as clearly indicated in Fig. II. Mounted upon the shafts 15 and 16 and intermediately of the rollers 17 and 18 respectively, are the two cylindrical inking rollers 19 and 20. These

are preferably of a yielding composition of matter well known to the art. As so disposed and spaced, these inking rollers are intended to rotate successively across and 5 in contact with the ink distributing disk 3 and type-form 4. The upper inking roller 19 is fixed to the shaft 15. The lower inking roller 20 is somewhat shorter than the roller 19 and is loosely mounted upon its 10 shaft 16 for a purpose which will herein-after clearly appear. The adjustment of the rollers 19 and 20 relatively to each other is accomplished in the usual manner through the medium of openings 21 and 22 and fas- 15 tening screws 23 and 24 respectively.

Centrally mounted upon the saddle 7 through the medium of two complementary and removable bushing forming members 25 is a third roller shaft 26. The position of 20 the shaft 26 is moreover somewhat higher with respect to the shafts 15 and 16. This shaft is in fact a spline shaft as indicated at 27 in each of Figs. II and III and for a purpose acknowledged as old in this par- 25 ticular art. The removal of the complementary bushing members 25 located on opposite sides of the saddle is accomplished through the medium of the cross-slides 28 and thumb screws 29. Positioned upon the 30 shaft 26 just inside one of the members 25 and so as to also lie in the same vertical plane as the rack 5 is a driving pinion 30. The positioning of this pinion is moreover such that it will lie in mesh with the driv- 35 ing gear 10. Mounted in the customary manner about the spline 27 so as to become in conjunction with another part to be described, both rotatable about and slidable upon it, is a slightly smaller ink-distribut- 40 ing roller or vibrator 31. This member is generally composed of metal and its inter-positioning with respect to the rollers 19 and 20 is such that it has a substantially uniform lineal contact of sufficient pressure 45 with each. The opposite end of the vibrator 31 is supported through the agency of the now well known screw threaded shaft 32 adapted to fit complementary screw threads in the member 25 employed on that par- 50 ticular end of the saddle; and incloses within its own opposite end the spline shaft 27 as sufficiently indicated, since not novel, in Fig. III.

The operation of my appliance should now 55 be recognized to be as follows: Assuming the saddle to be in its uppermost position upon the ink distributing disk 3; the vibrator 31 therefore, as suggested by the direction-of-movement arrows in Figs. I and 60 II, the maximum distance removed from the pinion 30; and the loosely mounted inking roller 20 abutting the subsidiary roller 18; it will be noticed first that the vibrator 31 is capable of sliding axially a greater dis- 65 tance than the inking roller 20. The rela-

tive extent of axial movement between the vibrator 31 and inking roller 20 is wholly arbitrary and it is for exemplification only that the extent of axial movement of the former is with due allowance for lost motion 70 about twice the extent of such movement on the part of the latter. It is however just this relative movement between these two rollers which comprises the essence of my invention. Accordingly, it is scarcely inapt 75 to particularly mention that the upper inking roller 19 might be similarly compelled to move in the direction of its own axis at a different ratio as regards extent. As the saddle proceeds downwardly the friction ex- 80 ereted by the vibrator 31 upon the inking rollers 19 and 20 suffices to carry the lower roller 20 along with it in an axial direction. Inasmuch now as the vibrator 31 is intended 85 to slide through its maximum extent during the time which it takes the saddle to travel from the top of the ink distributing disk 3 to the bottom of the type-form 4, and the extent of axial movement of the lower or inking roller 20 has been presumed, while 90 taking account of a variant friction between it and both surfaces (especially the type-form) over which it passes to be one-half; it is obvious that the roller 20 will abut the subsidiary roller 18 which it is approach- 95 ing and hence come to a stop as regards its axial movement when the saddle is passing over the apex 2. Consequently, the inking roller 20 is compelled to pass over the type-form on its downward trip in the same man- 100 ner that the upper inking roller 19 does. As contradistinguished, on its return trip, due to the sliding of the vibrator 31 in the reverse direction, the inking roller 20 will 105 pass upwardly over the type-form in a helical direction with respect to its own axis. It is the occasioning of such a different line of travel of the inking roller 20 over the type-form which is calculated to effect an approximate consummation of uniform ink 110 distribution. The lines of travel of the inking roller 20 over the ink distributing disk 3 are similar save that the order of the different routes of travel is reversed. In the meantime, the function of the vibrator 31 115 has been in no wise impaired, merely added to. It should be noted also as of practical advantage, that on gears or pinions are mounted upon the shafts of either of the rollers 19 or 20, hence the adjustment of 120 these two rollers, made necessary by gradual wear, is possible without bringing about a binding effect between such enmeshed gears or pinions.

Having now fully described my invention, 125 what I claim and desire to secure by Letters Patent is:

1. An appliance of the character described comprising the combination of a track, a saddle, a pair of inking rollers, mounted on 130

the latter and movable upon said track, one of said rollers being slidable in the direction of its own axis, a distributing roller superimposed upon said inking rollers so as to have frictional contact therewith, actuating means positively connecting said track and distributing roller, mechanism connecting said actuating means with said distributing roller for automatically sliding the latter in the direction of its own axis, and means for adjusting one of said inking rollers with respect to said distributing roller.

2. An appliance of the character described comprising the combination of a track, a rack therealong, a saddle, means including a gear for reciprocating said saddle, an inking roller rotatably mounted upon said saddle and slidable in the direction of its own axis, a distributing roller also mounted upon such saddle and superimposed upon said inking roller so as to have frictional contact therewith, said distributing roller being operatively connected with said gear, mechanism connecting said reciprocating means with said distributing roller for automatically sliding the latter in the direction of its own axis, and means for adjusting said inking roller with respect to said distributing roller.

3. An appliance of the character described comprising the combination with an inking disk and type-form; of a saddle mounted above and adapted to move thereacross, means for reciprocating said saddle, an inking roller upon said saddle and adapted to contact said inking disk and type-form, said roller being slidable in the direction of its own axis, a vibrator upon said saddle and superimposed upon said inking roller so as to have frictional engagement therewith, means controlled by said reciprocating means for sliding said vibrator axially a given distance, and means for regulating at fixed predetermined intervals the friction exerted upon said inking roller.

4. An appliance of the character described comprising the combination of a type-form, a saddle mounted for movement across said type-form, an inking roller supported upon said saddle and rotatable upon said type-form, said roller being slidable in the direction of its own axis, means for reciprocating said saddle, a distributing roller also supported upon said saddle and superimposed upon said inking roller so as to have frictional lineal engagement therewith, the axes of said rollers being substantially parallel, and means for sliding said distributing roller axially a greater distance in the same direction as said inking roller for each reciprocation of the saddle.

5. An appliance of the character described

comprising the combination of a type-form, a saddle, means for actuating said saddle, a pair of inking rollers mounted upon said saddle and rotatable upon said type-form parallel with the direction of movement of said saddle, one of said rollers being slid- 65 able in the direction of its own axis, a distributing roller mounted upon and having frictional contact with said inking rollers, said last mentioned roller being parallel with said first mentioned rollers, means connected with said actuating means for sliding said distributing roller transversely to the direction of travel of said saddle, said distributing roller being adapted to draw said inking roller along with it, and independently operating means for limiting such 80 concerted transverse movement of said axially slidable rollers.

6. An appliance of the character described comprising the combination of a roller, a second roller having peripheral contact therewith, means for reciprocating said rollers together, and automatically operating means for successively sliding said rollers axially together with each other and one independently of the other.

7. An appliance of the character described comprising the combination of a saddle, means for reciprocating said saddle, an inking roller thereon and slidable in the direction of its own axis, a distributing roller 95 also mounted on such saddle and superimposed upon said inking roller so as to have frictional contact therewith, means for adjusting one of said rollers with respect to the other, mechanism connecting said reciprocating means with said distributing roller for automatically sliding the latter in the direction of its own axis, the extent of axial travel of said distributing roller being adjusted to exceed that of said inking roller by 105 a predetermined amount for each direction of movement of said saddle.

8. An appliance of the character described comprising the combination of a saddle, means for reciprocating said saddle, an inking roller thereon and slidable in the direction of its own axis, a vibrator on such saddle and superimposed upon said inking roller so as to have frictional contact therewith, means connected with said reciprocating means for automatically sliding said vibrator in the direction of its own axis and means for arresting the sliding movement of said inking roller intermediately of the positions of rest of such saddle.

Signed by me, this 21st day of Nov., 1912.
